(57) **CLAIM**

The ornamental design for an X-ray image capture device for medical use, as shown and described.

DESCRIPTION

FIG. 1 is a first perspective view of an X-ray image capture device for medical use showing the new design;

FIG. 2 is a second perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a cross sectional view thereof along line 9-9 omitting the internal configuration.

The broken lines shown in the drawings of the X-ray image capture device for medical use illustrate the environment of the claimed design and form no part thereof.

The alternate dot-dash line merely indicates a boundary between the portion for which design registration is sought and other portions.
